DESIGN FOR AN EYE MASK

Frances A. Rentchler, Mamaroneck, N. Y.

Application January 9, 1937, Serial No. 66,968

Term of patent 7 years

To all whom it may concern:

Be it known that I, Frances A. Rentchler, a citizen of the United States of America, residing at Mamaroneck, county of Westchester, State of New York, have invented a new, original, and ornamental Design for an Eye Mask, of which the following is a specification, reference being had to the accompanying drawing, forming part thereof.

Fig. 1 represents a front elevation of an eye mask showing my new design;

Fig. 2 represents a top plan view; and

Fig. 3 represents a side elevation of the same. The dominant features of the design are, a

base mask comprising eye members, each conforming generally to the configuration of the eye socket and concavo-convex in form, the eye members being connected by a nose bridge, and each eye member having a narrow slit lengthwise substantially centrally of its height; and an ornamental shield at least as long as an individual eye member superimposed on the convex outer surface of each eye member of the eye mask.

I claim:

The ornamental design for an eye mask, as shown and described.

FRANCES A. RENTCHLER.
